METHOD OF FRACTIONATING GASOLINE-LIKE HYDROCARBONS

Cary R. Wagner, Chicago, Ill., assignor to The Pure Oil Company, Chicago, Ill., a corporation of Ohio

Application February 25, 1932, Serial No. 595,120

4 Claims. (Cl. 196—94)

This invention relates to improvements in the art of fractionating and distilling low boiling paraffinic hydrocarbons, whereby to obtain as a final distillate a gasoline of improved quality for use as a motor fuel.

Gasolines obtained by the distillation of certain crude oils such, for example, as those produced in the Michigan field, are composed of paraffinic hydrocarbons of a highly saturated order and contain high percentages of normal heptane, normal octane and normal nonane. Due to the presence of the saturated hydrocarbons specified in such gasoline, the latter possesses, at present, but relatively low value as a fuel for modern internal combustion engines, since hydrocarbons of the type specified, when employed as a motor fuel, produce knocking or detonation, and with certain types of the more highly developed internal combustion engines having high compression ratios, the use of such fuel is practically impossible in the performance of desired engine operation.

I have found that by careful fractionation, in a manner hereinafter specified, normal heptane, normal octane and normal nonane may be removed from gasoline vapors, whereby when the latter are condensed and used as a motor fuel, the said fuel will possess greatly improved properties in the matter of suppressing or minimizing detonation in the cylinders of an internal combustion engine when burned therein.

For a further understanding of the invention, reference is to be had to the following description and the accompanying drawing, wherein the figure indicates diagrammatically apparatus employed in the carrying out of the present invention in one of its preferred embodiments.

Referring more particularly to the drawing, the numeral 3 designates a tank adapted to contain crude oil, such as that obtained from or having the characteristics of Michigan crude. This oil is charged to a series of heated fractionating towers, which towers are designated in their order of operation by the numerals 4, 5, 6 and 7. Preferably, these towers are of standard construction but should be capable of effecting sharp fractionation and since there are many fractionating towers now available having this desired property, it is considered unnecessary to describe and illustrate in detail the structural features of such a tower.

The oil from the tank 3 enters the bottom of the tower 4 and is therein heated to vaporize low boiling compounds. These vapors are subjected to the action of descending reflux condensate so that the vapors discharged from the upper end of the tower through the pipe line 8 will comprise a light cut having an end point of approximately 190° F. From the side of the tower 4, there is taken off a stream containing

fractions boiling between 190° F. and 305° F., while a topped crude will be removed from the bottom of the tower 4 by way of the line 9.

This topped crude is conducted by way of the line 9 to the heated lower part of the tower 7, the final tower in the series, and the remaining gasoline fractions are removed from the crude at this point. The side stream taken from the tower 4 passes through a pipe line 10 and is delivered to the heated lower portion of the second tower 5. This side stream contains normal heptane, normal octane and normal nonane together with two fractions of good gasoline hydrocarbons boiling in the ranges between the boiling points of the pure paraffin hydrocarbons mentioned. From the top of the tower 5 there will be removed as vapors hydrocarbons having a boiling range of approximately 190° to 210° F., and this fraction contains the normal heptane present in the crude. The condensate or residual oils, which collect in the bottom of the tower 5, represents a narrow boiling point fraction having a range of approximately 290° to 305° F., and this fraction contains the normal nonane content of the crude. This last described fraction containing normal nonane, is transferred from the bottom of the tower 5 by way of a pipe line 11 to a storage tank 12.

A side cut is taken from the tower 5 and is delivered to the heated lower portion of the third fractionating tower 6. From the top of this tower, a good gasoline fraction, having a boiling point range of from 210° to 240° F. is taken off, and from the bottom of the tower 6 another good gasoline fraction, having a range of 255° to 290° F. is taken off, while the normal octane fraction is taken out of the tower 6 as a side stream through a pipe line 13 with a distillation range of 240° to 255° F.

By combining the fractions from the top of the tower 4, the top of the tower 7 and from the top and bottom of the tower 6, there is secured a gasoline from which normal heptane, normal octane and normal nonane have been removed and which gasolines will have an octane number approximately the same as that of ordinary Mid-continent gasoline, which is approximately 50. Michigan straight run gasoline normally has an octane number varying between 15 and 30. Since the octane number of normal heptane is zero and normal octane and normal nonane are considerably below zero on the octane scale, and since approximately six to eight per cent. of the crude oil from the field mentioned consists of these three paraffin hydrocarbons, it will be apparent that a desired improvement is effected by the operation of the present invention in the combustion characteristics of such straight run gasoline. The desired gasoline is collected in a tank 14 and the vapors

lead from the top of the tower 4, the top of the tower 7 and the top of the tower 6 may be condensed as at 15 prior to their delivery to the tank 14 and, likewise, the liquid oils withdrawn 5 from the bottom of the tower 6 may be cooled before entering the tank 14.

What is claimed is:

1. In the non-destructive distillation of crude oils composed largely of saturated paraffinic hydrocarbons, the process which consists in subjecting such crude oil to distillation in a plurality of serially connected heated fractionating and distilling zones, removing as vapors from the first of said zones vaporized hydrocarbons 15 having a boiling range below that of normal octane, normal heptane and normal nonane, removing from an intermediate portion of the first of said zones hydrocarbons falling within the boiling range of gasoline and containing 20 normal nonane, normal heptane and normal octane, subjecting said latter hydrocarbons in a second fractionating zone of distillation, removing from the upper portion of the second fractionating zone hydrocarbons containing normal 25 heptane, removing from the lower portion of said second fractionating zone hydrocarbons containing normal nonane, transferring hydrocarbons containing normal octane from an intermediate portion of said second fractionating zone to a 30 third fractionating zone, heating the hydrocarbons in the third fractionating zone to effect the removal from an intermediate portion of this latter zone of hydrocarbons containing normal octane, and collecting and condensing hydrocarbons removed from the upper portion of the first 35 fractionating zone and the upper and lower portions of the third fractionating zone.

2. The method of improving the anti-knock rating of straight run gasolines which comprises 40 subjecting crude oil containing such gasoline to distillation in a fractionating zone, removing from the upper portion of said fractionating zone in a vaporous state hydrocarbons having a boiling range lower than that of normal 45 nonane, normal heptane and normal octane, removing from an intermediate portion of said fractionating zone and delivering the same to a second fractionating zone hydrocarbons containing normal heptane, normal nonane, normal 50 octane, subjecting the hydrocarbons in the second fractionating zone to distillation whereby to remove from the upper portion of this zone hydrocarbons having the boiling range of normal heptane, removing from the lower portion 55 of the second zone hydrocarbons having the boiling range of normal nonane, and removing from an intermediate portion of the second zone hydrocarbons containing normal octane, transferring the hydrocarbons containing normal 60 octane to a third fractionating and distilling zone, removing as vapors from the upper portion of the third zone hydrocarbons having a boiling range lower than normal octane and substantially free from normal heptane and normal 65 nonane, removing from an intermediate portion of the third zone hydrocarbons composed of and falling within the boiling range of normal octane, transferring residual oils from the bottom of the first zone to a fourth distilling and fractionating zone, condensing and collecting vapors removed from the upper portions of the first, third and fourth fractionating zones and oils removed from the lower portion of the third zone to provide an improved gasoline sub-

stantially free from normal nonane, normal heptane and normal octane, and removing from the bottom of the fourth zone oils having a boiling range higher than that of gasoline.

3. The method of fractionating gasoline vapors of the type containing normal heptane, normal octane, and normal nonane which consists in passing such vapors through a first fractionating zone, removing from the upper portion of said zone vapors of hydrocarbons boiling below 10 approximately 190° F., removing from an intermediate portion of the fractionating zone hydrocarbons having a boiling range of approximately 190° to 305° F., passing said latter hydrocarbons through a second fractionating zone, removing 15 from the top of the second fractionating zone vapors of hydrocarbons boiling between approximately 190° to 210° F. and containing normal heptane, removing from the lower part of the second fractionating zone hydrocarbons having a boiling range of from 290° to 305° F. and containing normal nonane, removing from an intermediate part of the second fractionating zone hydrocarbons boiling between approximately 210° F. and 290° F., passing said latter hydrocarbons through a third fractionating zone, removing from the top of the third fractionating zone hydrocarbons having a boiling range of approximately 210° to 240° F., removing from an intermediate portion of the third fractionating 30 zone hydrocarbons having a boiling range of approximately 240° to 255° F. and containing normal octane, removing from the bottom of the third fractionating zone hydrocarbons having a boiling range of approximately 255° to 290° F., 35 transferring oils condensed in the bottom of the first fractionating tower to a fourth fractionating tower and removing vapors from the top of the fourth fractionating tower and condensing and collecting the same in common with vapors 40 and oils removed from the top of the first zone and from the top and bottom of the third fractionating zone.

4. The process for treating petroleum oils composed largely of hydrocarbons of the paraffin series and falling within the boiling range of ordinary gasoline to deprive such oils of undesirable fractions which impair the anti-detonating value of said oils as motor fuel, which comprises subjecting such oils to non-destructive 45 distillation to vaporize hydrocarbons contained therein falling within the boiling range of ordinary gasoline, fractionating said vaporized hydrocarbons and removing therefrom in vaporous form light hydrocarbons having a boiling range 50 lower than that of normal heptane, recovering from such fractionation a distillate composed of hydrocarbons having boiling ranges falling between and including those of normal heptane and normal nonane, subjecting said distillate to 55 redistillation and sharply separating therefrom as a vapor hydrocarbons composed solely of those falling within the boiling range of normal heptane, and recovering a distillate from said second distillation step composed of hydrocarbons having a boiling range higher than that of normal heptane and in excess of that of normal octane, subjecting said last-named distillate to redistillation 60 in a third zone, removing gasoline hydrocarbons in a vaporous state from said third zone, 65 and recovering a distillate removed from said third zone as normal octane.

CARY R. WAGNER.
